UNITED STATES PATENT OFFICE.

JAMES H. RAND, JR., OF TONAWANDA, NEW YORK.

CARD-INDEX DEVICE.

Application filed February 2, 1924. Serial No. 690,270.

To all whom it may concern:

Be it known that I, JAMES H. RAND, Jr., a citizen of the United States, residing at Tonawanda, in the county of Erie and 5 State of New York, have invented a new and useful Improvement in Card-Index Devices, of which the following is a specification.

This invention relates to followers or devices such as are used in connection with 10 trays or supports for record or index cards or card-holders for the purpose of maintaining the cards or card-holders in proper position on the trays or supports.

Card indices have been provided comprising trays or supports on which are positioned a plurality of cards or card-holders, these cards or holders being provided with flaps whereby the head of one card or holder may be inserted beneath the flap of 15 an adjacent card or holder to maintain them in nested, overlapping arrangement with the free edges of the cards projecting one beyond another in such a way that the cards lie substantially flat on the tray. The cards or holders are further provided with lugs or lateral extensions adapted to engage beneath side flanges or guide members on the trays or supports so that the cards or holders may be releasably connected thereto. Follower blocks or members have also been provided, having one or more portions for 20 engaging lugs or other parts on the trays and another portion adapted to engage the flap of one or more of the cards or holders 25 or to compress the cards or holders and maintain them in their nested, overlapping positions. The trays heretofore also have been provided, preferably at their front ends, with a card or card-holder supporting part 30 extending across the tray above the follower and adapted to maintain the cards or holders adjacent that end of the tray in a position such that their ends will be in substantially the same plane, or in alinement with the 35 other cards or holders of the series, said supporting member also providing a rest whereby the adjacent cards may be conveniently supported while being worked upon, and while the follower is being 40 actuated. Followers of the sort mentioned, however, are of fixed length and depend upon the pressure or inherent resiliency of

the cards or holders for support in one direction. Therefore, if the cards or holders are not fully compressed when the follower is placed in operative position or should the cards or holders, after use, become more closely nested together or lose some of their initial resiliency and thereby relieve some of the resistance against the follower, the follower, or the cards or holders, or both, may become disengaged from the tray or support.

One of the objects of the present invention is to provide a follower for the purpose 65 stated, which is resiliently compressible and expansible and which will automatically adjust itself to compensate for variations in compression or resistance in the card series so that the follower will be maintained in 70 proper operative engagement with the cards and with the tray at all times, regardless of such variations; also to construct a follower which may be easily and quickly inserted in the tray or removed therefrom and which 75 will firmly maintain in position a varying number of cards or holders, and will prevent the unintentional removal thereof.

Another object is to construct a follower of this character having a part adapted to 80 support the body portions of the cards or holders adjacent thereto in proper alinement with the other cards of the series, whereby the fixed card-supporting plate or part usually provided at the front end of the 85 trays for this purpose may be eliminated.

Other objects are to provide a follower of this sort which, in addition to its usual function of compressing and holding the cards in position on the tray, is adapted to be 90 moved to a position in which one or more of its parts will form a support for the cards or holders after they have been actuated or moved to a position in which they extend outside of, or beyond the tray; also to construct a 95 follower having relatively few and simple parts which may be inexpensively produced, as in the form of sheet metal stampings, and if desired, to provide such followers with means whereby they may be actuated from 100 outside of the tray; also to improve and simplify the construction of followers of this sort in the other respects hereinafter specified and claimed.

In the accompanying drawings:

- Fig. 1 is a plan view of a portion of a card index tray or support provided with a resiliently compressible and expansible follower device constructed in accordance with a preferred form of the invention.
- Fig. 2 is a bottom plan view, on an enlarged scale, of the follower, detached from the tray.
- Fig. 3 is a longitudinal sectional elevation, on an enlarged scale, on line 3—3, Fig. 1, but showing the follower compressed as when being inserted in or removed from the tray.
- Fig. 4 is a similar view on line 4—4, Fig. 1, with the follower in operative position.
- Fig. 5 is a bottom plan view of a resiliently expansible and compressible follower of modified form.
- Fig. 6 is a fragmentary plan view of a card index tray or support provided with the modified form of follower.
- Fig. 7 is a longitudinal sectional elevation thereof on line 7—7, Fig. 6.
- Fig. 8 is a similar view, showing the follower moved to its card-releasing position on the tray, in which position it is shown as supporting a number of cards which have been moved to a position wherein they extend outwardly beyond the tray.
- Fig. 9 is a transverse section thereof, on line 9—9, Fig. 7.
- The present invention contemplates the provision of a resiliently expansible and compressible follower for the purpose stated, such that when in operative position on the tray or support it will be adapted to have a floating or resilient engagement between the series of cards and a part on the tray.
- The follower, as shown in the drawings, preferably comprises a card-engaging part, a tray or card-support engaging part, and means for resiliently connecting said parts so that they may have a floating or relative movement one with the other, whereby the follower may automatically adjust itself to variations in compression of the nested cards or holders so that it will always remain in operative engagement with and maintain the cards or holders on the tray or support.
- The tray may be of any suitable construction, that shown in the drawings including a bottom member or support A for the cards, side flanges B adapted to engage tongues C on the cards or holders D, which project laterally therefrom beneath the flanges B so that the cards are maintained in sliding engagement with the tray. The tray may also be provided with a fixed part or stop against which one of the series of cards or holders may abut to limit the extent to which the cards may be moved in one direction. Such a stop is shown at E, Fig. 4, which stop is adapted to engage the head of the rearmost card of the series.

In the preferred form of the invention disclosed in Figs. 1 to 4, a follower is shown which comprises, generally, a card-engaging member or part 10, a tray-engaging member 11 movably connected to the member or part 10, and resilient means adapted to exert pressure on said parts tending to normally force them in opposite directions away from each other. These resilient means may be in the form of a spring member 12 detachably secured to parts 10 and 11. The card-engaging member 10 is preferably formed of a substantially rectangular sheet metal part preferably extending substantially from side to side of the tray between the flanges B and having an edge 14 adapted to be inserted beneath the flap of the last card of the series. This edge, which is the rear edge in the construction shown, is preferably extended laterally at opposite sides of the member 10 to form lugs or ears 15 adapted to engage beneath the flanges B to guide the follower in its sliding movements in the tray. The side and front edges of the member 10 are preferably bent to form stiffening or strengthening flanges 16, 17 and preferably the side flanges 16 are tapered or of wedge form adapted to engage the bottom or back support A and hold the plate 10 in an inclined position beneath the cards D. The tray-engaging member 11 is also preferably in the form of a rectangular sheet metal part adapted to extend beneath the part 10 in sliding engagement with its lower face. The side edges 20 of this member 11 extend adjacent the flanges 16, and lugs 21, 22 on the member 10 extend downwardly and inwardly beneath and in engagement with the edges 20 and the under face of the member 11 and form guides therefor so that it may have sliding movements relative to the other part 10.

Suitable means are provided for inter-engaging the follower with a part of the tray. In the embodiment of the invention shown, the front edge 23 of the tray-engaging part 11 is formed with one or more offset extensions or fingers 24 extending outwardly and downwardly beyond said edge and adapted to engage beneath one or the other of a series of hooks or lugs 24^a on the tray part A adjacent its front end. As illustrated, these hooks may be arranged in pairs so that the follower will be held against turning or twisting in the tray. The flange 17 of the member 10 is preferably cut away or notched out as shown in Fig. 2, to permit free movement and passage of the fingers 24.

The resilient member 12, before mentioned, is shown as being formed of spring wire and provided with a central part 25 engaging under a hook or part 26 of a bridge member 27 on the card-engaging member 10. The spring 12 is further provided with oppositely extending expansible loops 28, the

free ends of which are restrained as by having bent portions adapted to engage under hooks or lugs 30 on the tray-engaging member 11. This arrangement is such that the loops 28 of the member 12 will tend to force the parts 10 and 11 in opposite directions, thus upon referring to Fig. 2, the edge 14 of the part 10 will be forced upwardly while the fingers 24 of the part 11 will be forced in the opposite direction, or downwardly. Stop shoulders or parts 31 on the part 11 are provided which are adapted to strike against a part of the member 10, as for instance the flange 17, to limit the relative movement of the parts 10 and 11. These two parts 10, 11 are preferably formed with apertures 32, 33, respectively. The bridge 27 of the part 10 extends transversely across the aperture 32, while a similar bridge member 34 formed by an edge of the aperture 33 and a turned-over flange 36 of the part 11 also extends across the aperture 32, substantially parallel with but at a distance from the other bridge 27. The purpose of these parts will now be explained.

In the use of the follower described, a desired number of cards or holders D are assembled flatwise in the tray and preferably, but not necessarily, in nested, overlapping arrangement therein, with their tongues C in engagement beneath the flanges B thereof. After pushing the series of cards towards the back stop E, the follower is inserted in the tray by grasping the bridge parts 27 and 34, and by pressing these parts towards each other the follower is compressed against the action of the spring member 12, and its length thereby shortened. The rear edge 14 may now be inserted beneath the flap of the last card or holder, as shown in Fig. 3, and the fingers 24 lowered to the position indicated in that figure. The follower should now be released, whereupon the spring member 12 will force the part 11 away from the part 10 and together with the reaction of the nested cards will cause the fingers 24 to firmly engage beneath the selected tray lugs or parts 24. It is desirable that when inserting the follower, as above described, it should be so positioned with reference to a pair of the lugs that when released, the fingers 24 will engage the selected lugs 24 before the shoulders 31 reach their stop position against the flange 17. In this way the follower will be permitted to have a floating or resilient action between its members 10 and 11 in both directions so that they will automatically act, through the spring member 12 to allow the follower to adjust itself or compensate for the varying compressions received thereby from the card series during the use of the tray. Further, the card series may be increased or reduced in number, without reducing the efficiency of the follower, by moving the fingers 24 into

engagement with one or another of the pairs of lugs 24 in accordance with the number of cards in the series.

As shown in Figs. 3 and 4, the card-engaging member 10 provides a surface 70 adapted to firmly support the adjacent cards in operative position, so that they may be readily worked upon, at the same time maintaining the free ends of these cards in substantially the same plane as the ends of remaining cards of the series, that is, substantially parallel with, or flat on, the support A.

The resiliently expansible and compressible follower may be constructed and arranged on the tray in different ways. In the modified form shown in Figs. 5-9, a follower is shown which is provided with a part whereby the follower may be actuated from outside the tray for the purpose of connecting and disconnecting it from the tray. This follower comprises, as before, two relatively movable and resiliently connected members 10^a and 11^a. The member 10^a has an edge 14^a adapted to engage a card or card-holder D', while the part 11^a has a slidably connection with the member 10^a by means of lugs 21^a, 22^a, and its front edge 36^a preferably passes outwardly beyond the front edge 17^a of the member 10^a through an aperture 36^b in that edge, see Fig. 9.

The follower is further provided with an actuating and locking stem or device 40. This device has a hinge or pivot connection 41 with the rear part of the member 11^a and its front portion extends outwardly through an aperture 42 in the front wall 43 of the tray, where it is provided with a knob or handle 44 for actuating it. This stem 40 is provided with means for releasably connecting it to a part of the tray so that the follower may be maintained in operative position. In the form shown in the drawings, a lug or tooth 45, stamped or otherwise formed on the stem, is adapted to engage a part of the tray, as for instance, an edge of the aperture 42 on the inner face of the wall 43 of the tray. The lug 45 thereby forms a stop to limit the outward movement of the part 11^a due to the pressure of the resilient spring member 12^a.

A flat spring 46 connected to the stem and bearing against the handle 44 normally holds the lug 45 in its stop or locking position, as shown in Fig. 7, and by pressing downwardly on the handle 44, the lug may be released to permit the stem 40 to be withdrawn. As shown in Fig. 8, outward movement of the stem 40 moves the follower parts 10^a and 11^a away from the card series on the tray, and permits the follower to take an inclined position relatively to the tray, in engagement with, and supported by the edge of the front wall 43. Any other form of locking and actuating means could be employed if desired.

The card index trays are sometimes arranged so as to be suspended in a substantially vertical or upright position. In such cases, the inclined position of the retracted follower just described is of advantage in that the member 10^a thereof then forms a convenient rest for a number of the cards during the time that the card series is being arranged or manipulated and also provides a firm support to permit these cards to be worked upon.

In the devices herein described, the followers are capable of automatically adjusting themselves to variations in compression or resistance from the cards or holders, while maintaining themselves at all times in firm contact with the cards and with the tray, thus preventing the cards, holders, or the followers from being jostled out of the tray when the tray is moved suddenly or dropped. The followers are easily and inexpensively constructed from sheet metal stampings, and they are adapted, in addition to their function as compressors, to form a convenient and smooth working support for the cards adjacent thereto.

I claim as my invention:

1. In a record-holding tray including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member having a part for engaging the other end of said series of record devices, and a part for engaging a portion of said tray, whereby said devices are resiliently compressed and maintained on said tray against said stop, said resiliently expansible and compressible member having a part adapted to support the free ends of the adjacent record devices and maintain them in substantial alinement with the free ends of the other devices of said series.

2. In a record-holding tray including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member having a part for engaging the other end of said series of record devices, and a part for engaging a portion of said tray, whereby said devices are resiliently compressed and maintained on said tray against said stop, said record-device-engaging part of said resiliently expansible and compressible member being adapted to

extend under the adjacent record devices to form a support for the free ends of said devices, whereby said ends may be maintained in substantial alinement with the free ends of the other devices of said series.

3. In a detachable stop for trays for supporting a plurality of record devices, the combination of a member having a part for engaging said record devices, a second member having a part for engaging said first member and a part for engaging a portion of a tray, and a resilient member having parts engaging each of said other members so that said other members are capable of resiliently expansible and compressible movements relatively to each other, said stop being adapted to normally expand to maintain said record-engaging part and said tray-engaging part thereof in engagement with said record devices and said tray respectively.

4. In a detachable stop for trays for supporting a plurality of record devices, the combination of a member having a part for engaging said record devices, a second member having a part for engaging said first member and a part for engaging a portion of a tray, and a resilient member having parts engaging each of said other members so that said other members are capable of resiliently expansible and compressible movements relatively to each other, said stop being adapted to normally expand to maintain said record-engaging part and said tray-engaging part thereof in engagement with said record devices and said tray respectively, and parts on said stop adapted to be moved towards each other to compress said stop against the action of said resilient member whereby said stop may be inserted into and released from engaging position with said record devices and said tray.

5. In a detachable stop for trays for supporting a plurality of record devices, the combination of a member having a part for engaging said record devices, a second member having a part for engaging said first member and a part for engaging a portion of a tray, and a resilient member having parts engaging each of said other members so that said other members are capable of resiliently expansible and compressible movements relatively to each other, said stop being adapted to normally expand to maintain said record-engaging part and said tray-engaging part thereof in engagement with said record devices and said tray respectively, a part on said first member and a part on said second member adapted to be grasped to move said members toward each other against the action of said resilient member, whereby said stop may be inserted into and removed from engaging position with said record devices on said tray.

6. In a record-holding tray including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member adapted to be inserted beneath a portion of said series of record devices to support the same and maintain the whole of said series in operative position against said back stop, said member having a part for engaging a portion of said series and a part for engaging a portion of said tray, a part for normally expanding said member to maintain said other parts in contact with said series and said tray portion, and means whereby said member may be compressed against the action of said expanding part to permit the removal of said member from said tray.
7. In a record-holding tray including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member adapted to be inserted beneath a portion of said series of record devices to support the same and maintain the whole of said series in operative position against said back stop, said member having a part for engaging a portion of said series and a second part for engaging a part on said tray, said second part being slidably connected to said first part, a resilient spring member connected to said first and said second parts to normally expand said member and hold the same in its operative engaging position, and a part on each of said members adapted to be pressed to force said members towards each other to compress said member to disengage it from said tray.
8. In a record-holding tray, including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member having a part for engaging the other end of said series of record devices, and a part for engaging a portion of said tray, whereby said devices are resiliently compressed and maintained on said tray against said stop, said resiliently expansible and compressible member having a part adapted to lie beneath and support a part of said series in operative position in said tray, and said member being adapted to be moved so that said supporting part may support a portion of said series in a position outside of said tray.
9. In a record-holding tray, the combination of a stop part for engaging an end of a series of record devices on said tray to prevent movement of said series in one direction longitudinally of said tray, a resiliently expansible and compressible member having a part adapted to engage another end of said series, and a part on said member having a portion engaging a part of said tray, a portion extending outside of said tray, and means whereby said tray-engaging portion may be held in such engagement whereby said member may be maintained in operative relation to said series to hold them in position against said stop, said outwardly extending portion being adapted to be actuated to disconnect said tray-engaging portion and permit said member to be moved to and from operative record-engaging position.
10. In a record-holding tray including a supporting part on which a series of record devices are adapted to be maintained in overlapping relation substantially parallel with said supporting part with their free edges exposed one beyond the other, the combination of a back stop on said tray against which one end of said series is adapted to abut, and a resiliently expansible and compressible member having a part for engaging the other end of said series of record devices, and a part for engaging a portion of said tray, whereby said devices are resiliently compressed and maintained on said tray against said stop, said resiliently expansible and compressible member having a part adapted to lie beneath and support a part of said series in operative position in said tray, and a part extending to the outside of said tray, said part being adapted to be actuated to disconnect said tray-engaging part and permit said member to be moved from its record-supporting position on said tray to a record-supporting position outside of said tray.
11. In a record-holding tray including a supporting part on which a series of record devices are adapted to be maintained in overlapping relation substantially parallel with said supporting part with their free edges exposed one beyond the other, the combination of a back stop on said tray against which the end of said series is adapted to abut, and a resiliently expansible and compressible member having a part for engaging the other end of said series of record devices, and a part for engaging a portion of said tray, whereby said devices are resiliently compressed and maintained

on said tray against said stop, said resiliently expansible and compressible member having a part adapted to lie beneath and support a part of said series in operative position in said tray, and a part extending to the outside of said tray, said part being adapted to be actuated to disconnect said

tray-engaging part and permit said member to be moved from its record-supporting position on said tray to a position outside of said tray and out of engagement with said series of record devices to permit said devices to be removed from or adjusted on said tray. 10

JAMES H. RAND, JR.
